UNITED STATES PATENT OFFICE.

EDMUND JANSEN, OF SOLINGEN, PRUSSIA, GERMANY.

POCKET-KNIFE.

SPECIFICATION forming part of Letters Patent No. 399,047, dated March 5, 1889.

Application filed September 19, 1888. Serial No. 285,780. (No model.)

To all whom it may concern:

Be it known that I, EDMUND JANSEN, manufacturer, a subject of the King of Prussia, German Emperor, residing at Solingen, in the 5 Kingdom of Prussia, German Empire, have invented certain new and useful Improvements in Pocket-Knives, of which the following is a specification.

My invention relates to and about pocket-knives; and it consists in the manner of holding the blades in their open position by a slide, and thus doing away with the usual back-spring and allowing of a simple fixing of the blade.

15 In order to make my invention more clear, I refer to the accompanying drawings, which form part of this present application, and in which similar letters denote similar parts throughout the different figures.

20 Figure 1 is a longitudinal section of my improved pocket-knife when closed. Fig. 2 is a longitudinal section of the same with the slide released to allow of the blade being opened. Fig. 3 is a longitudinal section of 25 the same with the blade full open and fastened in that position by means of the slide b. Fig. 4 is a back view of the knife when open. Fig. 5 shows a modification of the manner of holding the slide b in its shut and open positions by a groove, v, and shows the blade fastened when in its open position. Fig. 6 is the same, but with the slide b drawn back, so as 30 to allow of the blade being closed.

The knife is of the common form and construction, and consists of a usual knife-case, 35 d, of any desirable material, and of the knife blade or blades a, hinged at s to the case. A guide-piece, f, is secured to the back of the blade a by way of dovetail. A slide, b, is secured to this guide-piece.

The slide b may be brought into the posi-

tions as illustrated in Figs. 1 and 2. In the position Fig. 1 the blade is secured in its closed state. In the position Fig. 2 the knife may be opened.

45 The slide b only allows the opening of the knife when in the position Fig. 2.

In the opened state of the blade a the slide b is shoved in the right-hand direction, as 50 illustrated in Fig. 3, and the blade is secured in the simplest and easiest manner. The hook v may be added for extra security. This construction offers complete security against unintended opening or closing of the blade, and by dispensing with the back-spring the manufacture of my improved knives becomes less 55 expensive. I state, finally, that the before-described arrangement may be used in connection with any desirable form of pocket-knives.

Having fully described my invention, what I desire to claim and secure by Letters Patent of the United States is—

1. In pocket-knives, the combination of a hasp, d, blade a, and sliding clasp b, the said 65 clasp b being loosely fastened to the blade a and sliding over the end of the clasp d, so as to keep the blade from accidentally opening or shutting, substantially as described.

2. In pocket-knives, the combination of a 70 hasp, d, blade a, having a hook, v, and sliding clasp b, the said clasp b being loosely fastened to the back of the blade a by the guide-piece f, so as to slide over the end of the clasp d, substantially as and for the purpose de- 75 scribed.

In witness whereof I have hereunto set my hand in presence of two witnesses.

EDMUND JANSEN.
